Specification for Design.

Patented Apr. 13, 1915.

Application filed February 7, 1914. Serial No. 817,357. Term of patent 3½ years.

To all whom it may concern:

Be it known that I, ROBERT B. GRIFFIN, a citizen of the United States, and a resident of the borough of Manhattan, city and State of New York, have invented a new, original, and ornamental Design for Fabric, of which the following is a description.

The design may be applied to any fabric, but it is especially intended to be applied to cretonne, wall paper or other wall covering.

The design is represented in the accompanying drawing and in applying it to the fabric it may be repeated as often as desired in the usual manner.

As shown in the drawing, the design is illustrated in black and white. It is to be understood, however, that the background A, the flowers B or the birds C, shown in the drawing may be colored or tinted as desired.

I claim:

The ornamental design for a fabric as shown and described.

In testimony that I claim the foregoing as my own, I have hereto affixed my signature in the presence of two witnesses.

ROBERT B. GRIFFIN.

Witnesses:

C. THOMPSON,
HARRY SLAVIN.
